CLAIM

The ornamental design for a probe for electronic clinical thermometer, as shown and described.

DESCRIPTION

FIG. 1 is a top, front, right side perspective view of a probe for electronic clinical thermometer showing my new design;

FIG. 2 is a front elevational view;

FIG. 3 is a rear elevational view;

FIG. 4 is a right side elevational view, the left side elevational view being identical;

FIG. 5 is a top plan view;

FIG. 6 is a bottom plan view; and

FIG. 7 is an enlarged cross-sectional view as taken from line VII—VII FIG. 2 thereof.
